TYPEWRITING MACHINE

Meigs W. Newberry, South Windsor, Conn., assignor to Underwood Elliott Fisher Company, New York, N. Y., a corporation of Delaware

Application December 31, 1942, Serial No. 470,880

18 Claims. (Cl. 197—63)

This invention relates to carriage stop mechanisms for typewriting machines, and has reference more particularly to a combined margin gaging and tabulating mechanism having key-settable stops.

One of the objects of the invention is to provide an improved carriage stop mechanism having provision for both margin gaging and tabulating and employing only a single series of key-settable stops adaptable to gage the typing line 10 margins and define the tabulating columns.

In providing a carriage stop mechanism in typewriters, adapted for both margin gaging and tabulating and employing only a single series of key-settable stops, the principal problem arising is that of devising a mechanism which will distinguish between stops set for gaging the margins and stops set to define tabulating points, as well as distinguishing between the left and right margin stops. In certain mechanisms heretofore proposed, this difficulty has been obviated by employing non-uniform or differently shaped stops for defining, respectively, the left and right margins, of which the patent to Dobson, No. 2,196,790 is typical. Other mechanisms have answered this problem by setting the stops which, in such instance, are uniform, to three different positions to define, respectively, the left and right margins and the tabulating points, of which the Austrian patent to Reiszer, No. 96,175 is an example. Still further mechanisms have been proposed in which the stops are set to corresponding positions to define each of the margins, and are set to a different position or extent of projection to define the tabulating points, as shown in the patent to Demmel, No. 2,247,014. These proposed mechanisms have, among others, the objections of the higher cost of manufacture in providing differently shaped or differently settable stops, and the need for frequent servicing because of stops being bent as a result of excessive overhang from the supporting structure.

In view of the foregoing, an object of the present invention is to provide a combined margin-gaging and tabulating mechanism in which only a single series of key-settable stops is employed and in which the stops are identical and are set to corresponding effective positions aligned with each other, that is, each of the stops is set to the same position with respect to its support whether set for defining the typing-line margins or the tabulating points.

Another object is to provide a carriage-stop mechanism including a series of uniform, settable stop members which, when effectively set for any

function, assume corresponding positions coextensive with each other, which mechanism will cause arrest of the carriage at one marginal point defined by certain set stop members, only while the carriage is moving in one direction, and will cause carriage arrest at another marginal point defined by other set members, only when the carriage is moving in the opposite direction, although one or more additional stop members may be set to define a number of tabulating points as well.

More specifically, an object is to provide a margin-counterstop mechanism for cooperation with the effectively set stop blades, all of which are arranged at letter-space intervals in a single series and assume identical positions when set, which mechanism will allow a single set stop blade to pass without interrupting carriage travel but will arrest the carriage upon passage of a pair of blades set at a certain relation to each other.

A further object is to provide a margin-gaging mechanism including a single series of identical letter-spaced blades settable to corresponding positions, including counterstop means adapted to arrest carriage travel in one direction, only upon coaction therewith of a pair of stops set at a certain space relation, and adapted to arrest the carriage when moved in the opposite direction, only upon coaction therewith of a pair of blades of a certain, different space relation.

A further object is to provide carriage-arresting means, including a single series of settable members arranged at letter-space intervals on the carriage, adapted to effect carriage arrest at one or more tabulating points defined by single set blades and adapted to arrest the carriage at one margin defined by a pair of set blades of one space relation and at another margin defined by a pair of blades set at another space relation, carriage arrest in any instance occurring only at the respective positions assumed by the carriage when the individual stops were set.

Another object is to provide, in a carriage-stop mechanism of this character, an improved means for setting the stop members of the series in various combinations to function respectively as stops of three different purposes, the set stops being distinguished from each other by being made up of either one or a pair of said members and further by having the pairs of members at different spacings, the setting means including only three stop-actuators and mechanism for operating these actuators in different combina-

tions to accomplish each of the three setting operations by actuating an appropriate key.

A further object is to provide, in a mechanism of the character indicated using a single series of stops settable to identical positions for any of the three functions, an improved line-end signal or bell-ringing mechanism which is actuated only by the stop set to define the line-end or right margin, and remains inactive when acted upon by the line-start-stop or the tabulating stops, although all such stops may engage the signal mechanism during travel of the carriage.

Another object resides in providing a device, associated with the tabulator stop setting mechanism, which prevents setting a tabulator stop so close to an adjacent set stop that the two stops, if so set, would simulate a margin stop and would thus operate to arrest the carriage at that point as though it were a selected margin instead of a tabulating point.

Other objects will hereinafter appear.

In each of the two embodiments of the invention illustrated, a series of settable stop blades are arranged at letter-space intervals on the carriage and when set assume corresponding positions in alignment. The stop blades are set either singly to define a tabulating stop or in pairs to define each of the margin stops. The two blades of the pair for one margin are differently spaced from each other than are the two blades of the pair for the other margin. Margin counterstop means is provided which includes sensing devices capable of distinguishing the various set stops one from the other according to their intended function. That is, the margin counterstop means operates in such manner that, although all of the set stops come into co-action therewith, the tabulator stops will be allowed to pass by without interrupting carriage movement and one of the margin stops will be arrested during travel of the carriage in one direction, and the other margin stop will be arrested during carriage travel in the opposite direction. The margin counterstop means is arranged to allow each margin stop to move past it in the direction opposite that in which the stop normally moves in arresting the carriage, without interrupting carriage travel. This action takes place after margin release, while the carriage is being restored to within the normal range of typing; the invention having provision for margin release which, when operated, allows the carriage to be moved beyond either margin point. A line-locking mechanism is provided to disable the typing instrumentalities when the carriage assumes a certain letter feed position as defined by the line-end margin stop, this mechanism being actuatable only by said stop. The novel line-end signal that is provided is so arranged that only the line-end margin stop will actuate same to signal the approach of a typing line end.

In the drawings:

Figure 1 is a sectional view through the typewriting machine embodying the invention, taken on a fore-and-aft, vertical plane of the typewriter and showing the carriage stop mechanism in side elevation; illustrating one embodiment which the invention may assume in practice;

Figure 2 is a front elevational view of the carriage stop mechanism shown in Figure 1, portions of the typewriter being omitted or broken away to facilitate illustration;

Figure 3 is an elevational view similar to Figure 2, but looking at the rear of the machine;

Figure 4 is a fragmentary front elevation taken on a vertical plane just to the rear of the margin counterstop mechanism and showing portions of the stop-restoring mechanism;

5 Figure 5 is a top plan view of the mechanism taken on a plane just below the typewriter platen and the stop rack;

Figure 6 is a fragmentary perspective view illustrating a portion of the tabulating mechanism;

50 Referring to the drawings, and particularly to Figure 1, the typewriting machine, in the two embodiments of the invention illustrated, has a carriage 17 supported on the main frame of the 55 machine for line-typing and return movement by a carriage rail 18 moving on a trackway 19, and a guide rail 20 and cooperating roller. The typewriter may include the usual typing instrumentalities having keys, not shown, for actuating type bars 21 to strike a platen 22 on the carriage. The carriage is actuated in letter-feed direction by the usual spring drum, not shown, under control of an escapement mechanism 23, the wheel 24 of which may be geared to the carriage by a pinion 25 and a carriage rack 26. The carriage may be advanced step-by-step in the conventional manner by the type bars engaging a universal bar 27 connected to a rockable bail 28 pivoted at 30 and having an operative connection 31 to an escapement dog carrier 32 cooperating with the escapement wheel 24 in the well-known manner. The arrangement of these mechanisms is such that during each type bar stroke the carriage is advanced one letter space

60 under control of an escapement mechanism 23, the wheel 24 of which may be geared to the carriage by a pinion 25 and a carriage rack 26. The carriage may be advanced step-by-step in the conventional manner by the type bars engaging a universal bar 27 connected to a rockable bail 28 pivoted at 30 and having an operative connection 31 to an escapement dog carrier 32 cooperating with the escapement wheel 24 in the well-known manner. The arrangement of these mechanisms is such that during each type bar stroke the carriage is advanced one letter space 65 in line-typing direction so that the type charac-

ters are successively imprinted in a typing line on a work sheet supported on the platen.

A series of stops or blades 34, identical in form, are arranged at letter-space intervals on the carriage and are supported by a rack bar 35 secured at each end to the carriage. Each stop blade 34 is slidable transversely in the rack bar for position-adjustment from an upper, inactive setting to a lower, effective setting at which the stop blade is disposed to cooperate during carriage travel with certain counterstop means, hereinafter described. A detent spring, not shown, is provided to yieldably hold the blade at either of said positions. The stop blade and rack arrangement may be of any suitable kind; that illustrated herein being the arrangement shown and described in the patent to Helmond No. 2,146,821.

In accordance with the invention, the stop blades 34 are set in different combinations according to the purposes for which they are intended, the various stops differing one from the other, either by the number of blades set (one blade for tabulating, two blades for margin gaging) or by the spacing of the two blades of the respective stops from each other (one letter space apart for the left margin, and more than one, preferably three, letter spaces apart for the right margin, or vice versa). In cooperation with certain counterstop means, hereinafter described, which include sensing devices to distinguish the various set stops, the single blade stops, having no companion stop blade, will operate only as tabulator stops; the double stop blade or pair of blades one letter space apart will act only as a left-margin stop, and the pair of stop blades three letter spaces apart will act only as a right-margin or line-end stop. For clarity, the term "tabulator stop" hereinafter used signifies a single set stop blade (without a companion blade) and is indicated at 34^t in the drawings, and the term "margin stop" signifies a stop composed of two blades set to define one of the margins, such as the left margin stop 34^l or the right margin stop 34^r.

Stop setting

The mechanism for setting the stops is mounted on the main frame, in the embodiments shown. Accordingly, the selection of a stop blade or pair of blades to be set for any of the three purposes may be effected by appropriately locating the carriage at whatever letter-feed point it is desired to set the stop. The setting mechanism of the first embodiment shown includes three setters 37, 38, 39, one for each kind or function of stop to be set; these setters including arms extending over the series of stop blades in position to engage and set the blade or blades aligned therewith. The setter 37, see Figures 2 and 3, is arranged to set the margin stop 34^l determining the line-start or left margin and, accordingly, has its blade-engaging portion arranged to engage two adjacent stop blades 34 that are one letter space apart and thus, when set, constitute a left margin stop 34^l. The setter 38 is adapted to set only the tabulator stops and, therefore, is arranged to engage only a single stop blade at a time to set it as a tabulator stop 34^t. The setter 39 provides for setting the right margin stop, for gaging the line end and for actuating the line-end signal and line-locking mechanism. This setter comprises two arms three letter spaces apart and sets two stop blades 34 at a corresponding spacing to constitute a right margin stop 34^r.

As shown more clearly in Figs. 1 and 5, the set-

ters 37, 38, and 39 are each carried on vertically slidable members 40, one for each setter. The upper portion of each member 40 is slidably guided in a plate 41 forming the top of a housing 42 secured to the main frame. Each setting member 40 is flexibly connected at its lower end to an intermediate lever 43 fulcrumed at 44 on a fixed bracket 45, see Figure 5. Each lever 43 has a spring 46 acting thereon to urge the corresponding setter 37, 38, 39 to its inactive or raised position. Individual key levers 47, one for each stop setter, are provided which reach forwardly to the region of the keyboard of the machine and are arranged to individually engage the corresponding levers 43. The arrangement of each train of setting mechanism 47, 43, 40 is such that, upon pressing any one stop-setting key lever, the corresponding stop setter 37, 38, or 39 is moved downwardly to engage and set the appropriate stop blade or blades 34.

It is desirable to prevent the setting of two tabulator stops 34^t as close together as three letter spaces in that two blades 34 set in this relation to each other would act as a line-end stop and would cause arrest of the carriage at a point other than the intended typing line limit. Accordingly, the invention provides a device, associated with the tabulator stop-setting mechanism, which prevents effective operation of this mechanism unless the blade 34 aligned with the setting arm 38 is at least five letter spaces away from the nearest set blade, whether this blade be a margin stop or another tabulator stop. This preventive device includes a feeler 50, see Figures 1 and 3, swingably mounted on a shaft 51 supported on the housing 42, said shaft forming an axis parallel with the direction of carriage movement and allowing the feeler 50 to swing transversely thereto. The member 40, carrying the tabulator-setting arm 38, includes a plate 52 in which a cam 53 is provided. A pin 54, projecting from said feeler 50, is arranged to cooperate with said cam.

As shown in Figure 5, the upper edge portion of the feeler 50 has a slot 55 which is in vertical alignment with the setting arm 38 and is amply wide to admit a single stop blade therein. From the slot 55, the feeler extends to each side an extent embracing four stop blades. The arrangement of the pin-and-cam connection 53, 54 is such that each time the tabulator-stop setting arm 38 is moved downwardly the feeler 50 is caused to swing forwardly, or leftwardly as viewed in Figure 1, with the result that the upper edge of the feeler is projected into the region where the stop blades are projected when being set, and thus occupies a range of four stop blades to each side of the tabulator stop-setting point defined by the setter 38. If any of the four stop blades 34 in this range has been set, the feeler 50 comes into engagement with that set blade and its forward swinging is obstructed and thus the effective operation of the setter 38 is prevented. If, however, no set blades are present within the range encompassed by the feeler 50, the latter is free to move forwardly incident to the tabulator stop setting operation, and a tabulator stop is set to effective position, the same projecting into the slot 55 of the feeler.

To avoid damage to the parts of the tabulator-stop-setting train, such as would result from a forceful operation of the corresponding key lever when effective operation is blocked by the feeler 50 engaging a stop already set, this mechanism provides a yieldable connection at the point be-

tween the member 40 and the corresponding intermediate lever 43. At this point, a pin-and-slot connection is provided, a spring 56, Figure 3, between lever 43 and member 40 taking up the slack in the pin-and-slot connection. The spring 56 is amply strong to be unyielding during the normal tabulator stop setting, but will yield upon being subjected to excessive force such as may be applied under the condition resulting when the feeler 50, engaging a set stop blade, prevents the full actuation of the associated key lever.

Counterstop means in general

It will be seen that the carriage stop mechanism of the first embodiment illustrated presents individual left and right margin counterstops 57, 58, respectively, Figure 2, and a tabulator counterstop 59, Figure 4. The tabulator counterstop is normally inactive, being yieldably held in a retracted position out of the path of the set stops 34, and is, therefore, not engageable by any of the set stops unless it is projected into the stop path incident to the tabulating operation, as hereinafter described.

The margin counterstops are each arranged in the stop path, but are not effective to arrest the carriage unless acted upon by an appropriately related pair of stop blades, that is, by the pair of blades set as at 34^l for the left margin, or as at 34^r, for the right margin. Each margin counterstop is normally ineffective or disabled, and each includes a device which conditions that counterstop for carriage arrest, only when acted upon by a particular set stop. Therefore, each counterstop will allow the other set stops to pass by without interrupting carriage travel. For example, the left margin counterstop 57 will bar carriage travel only when the margin stop 34^l, moving rightwardly, comes into cooperation therewith. Counterstop 57 will, however, allow the right margin stop 34^r and any tabulator stops 34^t to pass during travel of the carriage in either direction. Similarly, the right margin counterstop 58 will allow the left margin stop 34^l and the tabulator stops 34^t to pass by, and will arrest the carriage only when acted upon by the right margin stop 34^r moving leftward.

Margin counterstops

It will be seen in Figure 8 that the left and right margin counterstops each have substantially the same parts and are similar in construction and operating principle, differing only in certain respects hereinafter indicated. As shown best in Figure 7, each margin counterstop comprises, mainly, two interconnected members 60, 61 which cooperate directly with the respective corresponding margin stops 34^l, 34^r. The counterstop member 60 acts as a stop dog or pawl and has a tooth 62 with an abrupt shoulder on one side and an inclined face on the other side. The pawl 60 is pivoted intermediate its ends on a carrier member 63 by a stud 64 and has an angular opening 65 cooperating with a pin 66 on the carrier to limit the swing of said pawl. The other counterstop member 61 serves as a feeler or control member and is pivoted at one end thereof on the carrier 63 by a stud 67. A lug 68 at the end of pawl 60 opposite the tooth 62 engages a slot 69 intermediate the ends of the feeler 61 and forms the interconnection between these members 60, 61. The free end of the feeler 61 presents a tooth 70 projecting toward the path of the stops and providing a flat face substantially parallel to said path and inclined faces at each side thereof.

The two counterstop carriers 63 are pivotally mounted on a common support 72 on which a stud 73 for each carrier is engaged in an inclined slot 74 thereon. A spring 75, connected to each carrier 63 below the pivot 73, yieldably holds each carrier in its normal position with the lower end of each carrier engaging a stud 76. This mounting of the carrier 63 allows it to swing, under certain conditions of operation, to either side of its normal Figure 8 position; that is, taking the left counterstop 57, for example, in one phase of operation the carrier 63 thereof may swing clockwise about pivot 73, allowing the members 60, 61 to move rightwardly, as shown in Figure 9, and, in another phase of operation, the left carrier may swing oppositely, this time about stud 76 and thus allow the members 60, 61 to move leftwardly, see Figure 10. The angle of incline of slot 74 is relatively steep so that during this leftward movement of members 60, 61, the carrier 63 is cammed downwardly and therefore said members are caused to recede from the stop path in a sudden descent.

The support 72 is arranged for swinging leftwardly to a limited degree for the purpose of rendering effective certain line-locking devices hereinafter described, and is also shiftable toward or from the stop path so that the margin counterstops 57, 58 may be retracted from their normally raised positions to institute margin release. The support 72 extends downwardly and is articulated at its lower end to an intermediate lever 78 fulcrumed intermediate its ends at 44 on the bracket 45. A spring 79, Figure 5, tends to swing lever 78 clockwise, as viewed in Figure 2, thus yieldably holding the support 72 in its upper, normal position. A margin release key lever 80 pivoted intermediate its ends, has its rear end engaging the lever 78. Pressing the margin release key lever down at its forward end shifts the support 72 downwardly and thus retracts the counterstops 57, 58 from the stop path to effect margin release.

The upper portion of the support 72 presents two prongs 82, 83 between which a stud 84 on the plate 41 projects, forming a guide for the up-and-down sliding of said support and limiting its swinging movement. A spring 85, anchored on the bracket 45, urges the support 72 rightwardly and yieldably holds said support in its normal lateral position defined by engagement of prong 82 with the stud 84.

The prong 82 provides a stepped portion or shoulder upon which the pawl 60 of the left counterstop 57 may seat when said counterstop is shifted rightwardly, see Figure 9. The prong 83 provides a similar stepped shoulder on which the pawl of the right counterstop 58 may seat when that counterstop is shifted leftwardly.

Margin gaging

It will be seen that the two counterstop members 60, 61 are so interconnected that when the pawl member 60 is caused to swing downwardly, as by coaction of a set stop with its tooth 62, the feeler member 61 is swung upwardly; that is, its tooth 70 is projected into the path of the set stops. Conversely, when the feeler tooth 70 is depressed, the pawl tooth 62 is moved upwardly into stop path. This tumbling action of members 60, 61 is permitted as long as pawl 60 is clear of the stepped shoulder on the corresponding prong 82 or 83, and occurs during the passing of any set stop over the particular counterstop, except the particular margin stop that is set for car-

riage-arresting coaction with that counterstop. However, when the spacing of the two blades coincides with the spacing of the counterstop teeth 62, 70, arrest of the carriage results.

The arrest of the carriage at the line-start or left margin, upon returning the carriage to begin a new typing line, is demonstrated in Figure 9. It will be observed that the spacing of the tooth 70, of feeler 61 from the tooth 62 of pawl 60 corresponds substantially to the spacing (one letter space) of the two set stop blades forming the left margin stop 34^t. It may be said that when this spacing of the two counterstop teeth corresponds to the spacing of the pair of set stop blades, that counterstop is sensed or coordinated with that margin stop so as to effectively coact therewith and thus arrest the carriage. This coaction results from the fact that as the leading stop blade of the pair engages pawl tooth 62, the retraction of the pawl is prevented by the reaction of the feeler 61, the tooth 70 of which, tending to move upwardly, engages the trailing stop blade of the pair. Thus, as the blades of stop 34^t engage counterstop 57 the counterstop members 60, 61 maintain substantially their relative positions shown in Figure 8 and are thus caused to be moved en masse rightwardly as the carriage advances. This limited rightward movement is accommodated by the swinging of the carrier 63 about pivot 73 against the tension of spring 75 and ceases when the pawl 60 engages and seats on the stepped shoulder of prong 82, as shown in Figure 9. Thus, the pawl 60 is locked against receding from the stop path and the arrest of the carriage results.

The coaction of the right margin stop 34^r with its counterstop 58 is substantially the same in that the spacing of the teeth 62 and 70 of this counterstop corresponds substantially to the spacing (three letter spaces) of the two set blades constituting the right margin stop 34^r. This counterstop is, therefore, sensed or coordinated for carriage-arresting coaction with said margin stop and will cause the arrest of the carriage at the point at which said stop is set.

Stops passing counterstops

Where the two blades constituting the margin stop are not at a spacing which corresponds with the spacing of the teeth 62, 70 of the counterstop, that margin stop will pass by the particular counterstop without interrupting carriage travel. In allowing a stop to pass by, the members 60, 61 of the margin counterstop oscillate in opposite directions and the teeth 62, 70 thereon are accordingly moved up and down alternately. This tumbling action of members 60, 61 is demonstrated in Figure 11, where, at the left portion, a tabulator stop 34^t is shown passing the left margin counterstop 57. Assuming its motion to be rightward, the stop 34^t having passed beyond the feeler tooth 70 is now causing the pawl 60 to recede from the stop path. The pawl 60 is free to recede under influence of stop 34^t only because there is no companion stop blade to prevent the resultant rise of the feeler tooth 70. Assuming now that its movement is in the opposite or leftward direction, the stop 34^t will first cam the pawl 60 downward and the feeler 61 will consequently be raised. As stop 34^t progresses, it will cam the feeler downwardly and the pawl 60 will be brought up again behind said stop.

The action during the passing of the right margin stop 34^r by the left margin counterstop 57 is substantially like that just described for

the single tabulator stop 34^t in that the individual set blades of stop 34^r will coact separately with the members 60, 61 of the left counterstop 57, each blade coacting therewith the same as though it were a tabulator stop. As aforesigned, the teeth 62, 70 of the right counterstop 58 are spaced apart a distance corresponding to the spacing of the stop blades of the right margin stop 34^r; that is, three letter spaces. Therefore, any pair of set stops of a lesser spacing, such as the left margin stop 34^t, will pass by the right margin counterstop without interrupting carriage travel, as shown at the right of Fig. 11. The action shown there is substantially similar to that illustrated at the left of Figure 11 in that the two set stop blades constituting the left margin stop 34^t are so close together that they coact with the members 60, 61 of counterstop 58 as though they were, in fact, a single stop blade like stop 34^t.

Line locking

As the right margin counterstop 58 causes arrest of the carriage, its pawl 60 is moved leftwardly until seated on the shoulder of prong 82, substantially in the same manner as that shown in Figure 9 for the left margin gaging. Following this, however, additional movement of counterstop 58 takes place as afforded by the leftward shifting of the carrier support 72. The support 72 is shifted leftwardly until prong 83 engages the stud 84, which shifting actuates and renders effective the line-locking mechanism.

This mechanism is shown best in Figures 1 and 5 and includes a locking lever 86 pivoted at 87 and having its rear end portion engaged in a slot 88 of the shiftable support 72. The forward end of lever 86 terminates adjacent a lug 89 on the universal bar 27, being normally free of said lug to permit unencumbered vibration of the universal bar incident to the normal typing. When, however, the support 72 is shifted leftwardly incident to arresting the carriage at the typing line end, the lever 86 is thereby swung to locking position in which its forward end abuts the lug 89 and obstructs vibration of the universal bar 27. Thus, the swing of the type bars is limited so that they will not strike the platen, and the type actions are thereby locked against effective operation.

Margin release operation

When it is desired to type beyond either margin, release of the carriage for movement beyond the selected margin may be had by operating key lever 80 to retract the margin counterstops 57, 58, as aforesigned. When margin release is required, the carriage is already at the margin beyond which typing is desired and, therefore, the corresponding counterstop 57 or 58 is at its carriage arrest position, held there by the engaged margin stop, against the tension of spring 75 (also against spring 85, in the instance of the right margin). Just before release from the left margin, the mechanism is in the condition shown in Figure 9. Operation of the margin release key lever 80 causes the support 72 to be pulled down and thereby retracts the margin counterstop from the stop path. As soon as tooth 62 of the effective counterstop is clear of the engaged margin stop blade, the entire counterstop will swing bodily to one side of stop 34^t under the tension of spring 75, and will assume its inactive, leftward position. Because of this immediate displacement of the counterstop, key lever

80 may be released without first moving the carriage to the new position to avoid re-engagement of the stop 34^t, as has been the required practice with previous machines in releasing from the left margin.

Release of the carriage from the right margin, or line-end limit, operates in substantially the same manner except that the immediate return of the counterstop 58 to its rightward, inactive position involves the action of spring 85 as well as spring 75. That is, spring 85 causes the support 72 to be restored from its leftwardly displaced position and, in so doing, releases the machine from its line-locked condition by swinging lock lever 86 clear of the lug 89, Figure 5.

Line-end signal

In that the set stops for both tabulating and margin gaging are all aligned with each other lengthwise of the carriage, being set to identical positions on the carriage, all the set stops may come into engagement with the line-end signal mechanism during a carriage run in typing a line. The invention, however, provides an improved bell tripper device which will cause the actuation of the bell ringer only when acted upon by the line-end stop 34^r.

In the present embodiment, shown best in Figures 2 and 3, the line-end signal mechanism includes the usual bell 91 and a striker lever 92 both mounted on the main frame. The striker lever is pivoted at 93 on a bracket 94 and engages a limiting lug 95 which stops the lever 92 at a position in which its striking end is just clear of the bell. A spring 96, acting on lever 92 between the lug 95 and pivot 93, yieldably holds said lever in said inactive position. A slot in the lever 92 at pivot 93 allows the striking end of said lever to whip against the bell when said lever is released after being cocked preparatory to signalling the approach of the line end.

The upper portion of the striker lever 92 pivotally carries a tripper arm 97 which is yieldably held by a spring 98 in an upright position defined by a lug 99 on said arm engaging lever 92. Arm 97 swingably carries a tripper dog 100 which is adapted to distinguish the line-end stop 34^r from the others and thus cause actuation of the striker-lever only when acted upon by said line-end stop, allowing the other stops 34^t and 34^b to pass by without operating the signal mechanism. This action is obtained by providing the dog 100 with two high points or teeth 101 at opposite sides of the dog pivot, each tooth having inclined faces receding oppositely from the high point. When the tripper dog 100 is in the level position shown, the teeth 101 thereof each project into the stop path a corresponding distance, but the valley or low point between the teeth is below said path. The dog 100 is sensed or coordinated with the margin stop 34^r in that the teeth 101 of said dog are spaced one from the other a distance coinciding with or substantially equal to the spacing of the two blades constituting said stop. When stop 34^r comes into engagement with dog 100, as the leftwardly moving carriage approaches its position at the line-end limit, the leading blade of said stop 34^r rides over the first tooth 101 of the dog, and thereafter the two stop blades individually engage the two dog teeth simultaneously. Under this condition, the rocking of said dog on arm 97 is prevented in that the tendency of the one tooth to recede is counteracted by the other tooth which is blocked against being raised by

engagement with the corresponding stop blade.

With the two blades of stop 34^r thus engaged with the tripper dog 100, the carriage continues its letter-feed movement, leftward as viewed in Figure 2, and the bell striker lever 92 is thus 5 swung about its pivot 93, during which arm 97 is maintained in its upright position on the striker lever, by lug 99. Movement of the carriage continues until the stop 34^r rides off the tripper dog 100, whence lever 92 is released to 10 strike the bell 91. When the stop 34^r goes back over the bell ringing mechanism, moving rightwardly as viewed in Figure 2, the two stop blades engage the teeth of the dog in the same manner, but do not operate lever 92 in that arm 97 is 15 arranged to yield rightwardly, swinging about its pivot against the tension of spring 98. As soon as stop 34^r has moved a sufficient distance past the signal mechanism, the dog 100 is released and arm 97 resumes its upright condition.

The left margin stop 34^t will pass by the signal mechanism without operating same, because the spacing of its stop blades is less than the spacing of the dog teeth 101 and will therefore 20 engage only one of said teeth at a time, causing the dog 100 to merely rock about its pivot as each of the dog teeth is successively engaged. The line start stop 34^b will thus pass by the 25 line-end signal dog 100 in either direction of the carriage travel without actuating the signal mechanism. The tabulator stops 34^t will coact with the dog 100 in substantially the same manner, engaging the teeth 101 successively and 30 merely rocking the dog without actuating the mechanism. In that no two tabulator stops may be set closer than five letter spaces apart, two adjacent tabulator stops 34^t will coact with the 35 signal dog 100 individually.

Tabulating mechanism

By selective operation of the mechanism shown in Figure 6, the tabulator counterstop 59 may be caused to function either as the counterstop 45 in the tabulating operation, or may be operated either to individually restore the tabulator stops 34^t or collectively restore them during a run of the carriage. As shown in Figure 4, counterstop 59 is 50 slidable up and down in the top plate 41 and at its upper end provides a face 103 parallel to the direction of carriage travel and an inclined cam face 104. The face 103 serves in restoring the stops 34^t individually, and the cam face 104 operates to restore said stops successively during a return run of the carriage.

When counterstop 59 is operated to serve in the tabulating operation, same is projected into the stop path by actuation of a tabulator key lever 105 which also releases the carriage for a 55 tabulating run under influence of its spring. Lever 105 is fixed on a shaft 106 which is rotatably supported as shown in Figure 5 and has an upwardly reaching arm 107 secured thereon which, as shown in Figure 1, is arranged to coact with the escapement mechanism 23, in the well-known manner, to free the escapement wheel 24, as by releasing the holding dog of said mechanism, and thus releases the carriage to a tabulating run.

Lever 105 is operatively connected to the tabulator counterstop 59 by an arm 110, Figure 6, which is articulated to said lever by a pivot 111 and a yieldable connection 112. This connection includes a dog 113 on lever 105, which engages 70 a lug of arm 110. A spring 114 tensions arm

110 so as to hold the lug thereof against dog 113, said spring also tending to restore lever 105 to inactive position. The connection 112 is so arranged that it remains rigid when lever 105 is operated for tabulating, the swing of said lever during the depressing of its key being thus transmitted to arm 110. Said arm engages an offset 115 at the lower part of counterstop 59 and forms a yieldable device 116 thereto including a spring 117 interposed between arm 110 and offset 115. The connection 116 may yield when, in instituting a tabulating operation, the counterstop 59 is projected up under a set tabulator stop; the yielding avoiding restoration of that stop. The yielding at connection 116 allows the tabulator key lever 105 to be fully actuated, so that same may institute a tabulating run although counterstop 59 is not fully raised. The counterstop will, however, be urged upwardly by spring 117 until the engaged stop 34^t will have moved beyond the counterstop, whence the latter will snap up into the stop path in readiness to intercept the next approaching stop 34^t.

When the counterstop 59 is used to individually restore the stops 34^t, same must be projected forcefully, without yield, so as to overcome the resistance of the stop detent. To accomplish this, a second key lever 120 is provided, which is fulcrumed intermediate its ends on the shaft 106 to swing independently of said shaft. The rear arm of lever 120 provides a slot in which the lower portion of counterstop 59 is disposed, said counterstop also having a slot 121 through which the arm of lever 120 projects, thus forming a flexible and sliding connection between these members. A spring 122 restores lever 120 to quiescent position, assumed when said lever engages a limiting stud 123.

To restore all of the stops 34^t, key lever 120 is operated and the carriage is released from letter-feed control by the usual means, it being assumed that the carriage is at the line-end or leftward limit. Manual pressure is maintained on key lever 120 and the carriage is manually moved rightwardly to the extent defined by the margin-gaging mechanism. During this carriage travel, each tabulator stop 34^t rides up the cam face 104 on counterstop 59 and is thus restored to ineffective position in the stop rack. The restoring of the margin stops will not occur, in that travel of the carriage is limited to the range between said margins by coaction of the margin counterstops.

It will now be seen that the key levers 105 and 120 and the associated parts, comprise means by which the member 59 may be operated to function either as a tabulator counterstop or a tabulator stop restorer. When operating the key lever 120 for restoring a stop, the member 59 is projected into the stop path forcefully. During this operation, key lever 105 remains stationary in that the connection 112 yields to allow arm 110 to swing upwardly with member 59. When key lever 105 is operated, key lever 120 remains stationary in that the provision of slot 121 allows member 59 to be raised without transmitting motion to lever 120.

Restoring margin stops

The mechanism for restoring the two margin stops to ineffective position on rack 35, shown best in Figures 3 and 4, includes a member 125 for restoring the left margin stops 34^l and a member 126 for restoring the right margin stops 34^r. The member 125 is guided at its upper end

for up-and-down sliding in the plate 41 and extends downwardly, being flexibly connected at its lower end to an intermediate lever 127, the opposite end of which is engaged by a sub-lever 128 pivoted at 129, see Figure 5. A key lever 130, having a margin-stop restoring key at its forward end, has its rear end fulcrumed at 131 on the main frame. Intermediate the ends of lever 128, a pin 132 is provided which engages in a slot of key lever 130. This train of levers is so organized that upon depressing the key of lever 130, lever 128 is swung downwardly about its pivot 129 and causes the intermediate lever 127 to swing counterclockwise, as viewed in Figure 2, and thus raise the restoring member 125.

It will be noted that the member 125 has a width at its upper end ample to engage only the two closely spaced blades of the stop 34^l and is positioned directly below the point at which the stop 34^l comes to rest in gaging the left-hand margin. Upon operating key lever 130 with the carriage at the left-hand margin position, stop 34^l will be restored to ineffective position.

The restoring member 125 serves also to actuate the member 126, through a device which is normally ineffective but is rendered effective only when the carriage is arrested at line-end position; that is, only when the margin counterstop 58 and support 72 have been shifted rightwardly, as viewed in Figure 3, incident to gaging a right margin. As shown best in Figure 3, the counterstop supporting member 72 has a pivot 134 engaging in a slot of member 126, by which said member is arranged for pivotal and endwise movement on the support 72. The restoring member 125 has an arm carrying a pin 135 projecting into the plane of member 126 which has a notch 136 at its lower end into which said pin may seat. A spring 137 pulls the restoring member 126 downward and yieldably resists swinging of said member, maintaining it normally in the ineffective position shown in Figure 3, at which it is clear of pin 135 on the restoring member 125. Thus, member 125 may be operated to restore the stop 34^l without actuating member 126.

When, however, the carriage is at line-end position and the counterstop supporting member 72 has accordingly been shifted rightwardly, as viewed in Figure 3, this shifting, translated through pivot 134 to member 126, causes same to rotate slightly and thus assume the position shown in Figure 4, in which notch 136 is disposed in the path of pin 135. Under this condition, when the margin-stop restoring lever 130 is operated, the consequent raising of member 125 will also raise member 126 and thereby restore the two blades constituting the right margin stop 34^r. As soon as said stop is restored and the corresponding counterstop 58 is consequently released, the support 72 resumes its normal position. The resultant return of member 126 to the Figure 3 position renders the device 135, 136 again ineffective.

Relative arrangement of stop setters and counterstops

It will be noted in Figure 4 that the tabulator stop setter 38 is arranged a fraction of a letter space ahead of the face on the counterstop 59 which engages the tabulator stop 34^t, and that the setter 38 will set a stop blade just over the face 103 of counterstop 59. This arrangement is desirable in order that, after the tabulating operation, the stop 34^t is brought to rest at the

exact letter-feed point at which said stop was set. After being arrested by engagement with the right side edge of counterstop 59 following a tabulating run of the carriage, and after the counterstop is retracted, the stop 34^t advances the fractional letter space while the escapement mechanism resumes letter-feed control of the carriage, in the usual manner. Thus, incident to each tabulating operation, the effective stop 34^t will come to rest directly over the restoring face 103 of the counterstop, which position coincides with that at which the stop was set.

In the embodiment of the invention first described, the left and right margin counterstops 51, 58 are spaced from each other in the direction of carriage travel a minimum distance sufficient to accommodate the associated parts arranged therebetween, particularly the supporting member 72 with its prongs 82, 83. As previously described, these margin counterstops each move through a limited distance from their inactive positions before becoming effective to arrest the carriage; that is, in actual carriage-arresting position, the corresponding margin stops 34^t, 34^r are somewhat beyond their inactive positions at which they first engage their counterstops. Accordingly, the two margin stop setters 37, 39 are each arranged to set the corresponding margin stop at the position in the range of carriage travel at which that stop will have been arrested in gaging that margin.

Second embodiment of the invention

Reference is now made to Figures 12 to 16, inclusive, for a description of the modified form or second embodiment which the invention may assume in practice.

This embodiment also has the series of identical stop blades 34 arranged on the rack 35 for setting to an effective position, the set blades being in alignment with each other along the carriage. Also, the set stops are distinguished one from the others, according to the purposes for which they are intended, by being set in different combinations or permutations; that is, a single stop blade is set to function as a tabulator stop 34^t, in any desired number, two stop blades a certain letter-spacing apart represent a left margin stop 34^l, and two stop blades a different letter-spacing apart represent the right margin stop 34^r. In this second form, however, the right margin stop 34^r has its blades only one letter space apart and the left margin stop 34^l has its blades two letter spaces apart; a slight variation from the arrangement chosen in the first form.

It may be here noted that to modify the mechanism of either embodiment so as to employ a different prescribed position-relation of the stop blades of the respective margin stops, or to vary the order in which the several different stops may be set up on the carriage, is largely a matter of arbitrary selection and are variances well within the scope of the invention.

The primary difference in this form from the embodiment first described resides in the organization of the counterstop means that has to do with the margin gaging. In that the margin-counterstop means of this form operates to arrest the margin stops 34^l and 34^r at substantially identical positions in the range of carriage travel, further modifications are herein shown in the mechanism for setting the various stops. Other, minor changes may be noted as the description proceeds.

Margin-counterstop means of second form

The margin-counterstop means of the second inventive form includes a toothed wheel 140 rotatably mounted on a support 141, Figures 12 and 13. This wheel has a plurality of identical sets of teeth on its periphery, the several sets being spaced at substantially equal increments about the wheel. The wheel 140 preferably has four sets of teeth as it is found that this number provides an angular spacing of the teeth that is more suitable in its coaction with the various stops. During its coaction with the various stops, the toothed wheel may, under certain conditions, be rotated a prescribed degree equal to the angular spacing of the tooth sets, so that when the wheel comes to rest, the teeth thereof always assume a corresponding orientation, with one of the tooth sets uppermost. To control the degree of intermittent rotation, a detent device is provided, having a four-sided cam 142 arranged to rotate in fixed relation with the wheel 140. A detent roller 143 is carried on an arm 144 pivoted at 145 on the support 141, a spring 146 acting on said arm to press the roller 143 into detenting coaction with the cam 142. The arm 144 also carries a pin 147 arranged to function as a check dog in cooperation with cam 142 so as to augment the action of roller 143 in preventing overthrow of the toothed wheel 140. As the cam is rotated by the coaction of a stop with the toothed wheel, the resultant movement of the roller 143 causes the check dog 147 to closely follow the contour of the cam as same is rotated.

The supporting member 141 is so mounted that the toothed wheel 140 may shift laterally in either direction of carriage travel a limited distance, incident to arresting the carriage, or may be retracted from the path of the stops to effect margin release. This mounting of support 141 comprises a bracket 148 secured to a stationary part of the typewriter and providing a pivot 149 for a lever 150 articulated by a pin-and-slot connection 151 to the lower end of the support 141. A stud 152 on bracket 148 acts both as a rest and a pivot for support 141, and a spring 153 pulls on said support to yieldably hold same against the stud 152 and with the lower end of the support at the rightmost limit afforded by the connection 151. When the wheel 140 is shifted leftwardly by coaction of the stops therewith, the support 141 swings about the pivotal connection 151, and when shifted rightwardly said support swings on stud 152 as its lower end shifts at connection 151; the shifting in either direction being against the force of spring 153. The lever 150 forms part of the margin release mechanism which also includes a key lever, not shown, and by which the wheel 140 is retracted to a position wherein its teeth are out of the stop path.

Each set of teeth on wheel 140 includes a stop-intercepting tooth 155 and two sensing members together forming a tooth 156, the latter having two oppositely inclined, angular faces 157, 158, see Figures 14 and 15. The detent 142, 143 brings the wheel 140 to rest with one of the interceptor teeth projecting upwardly into the path of the stops. The spacing of each of the faces 157, 158 from the adjacent stop-engaging face of the tooth 155 determines the manner in which the wheel 140 coacts with a particular stop engaging same; that is, this spacing determines whether the particular stop will be arrested or allowed to pass by. Accordingly,

the tooth face 157 is spaced from the left face of the interceptor tooth 155 a distance substantially equal to the spacing of the two blades constituting the left margin stop 34^t, see Fig. 14. Similarly, the face 158 is spaced from the right face of the interceptor tooth 155 an amount approximating the spacing of the two blades constituting the right margin stop 34^r, see Figure 15.

When the wheel 140 is in its medial or unshifted position shown in Figure 12, not engaged by any of the stops, the two tooth faces 157, 158 at the opposite sides of the upwardly projecting tooth 155 are at a level just below the bottom ends of the set stops, clearing the stops so as to allow the leading blade of the corresponding margin stop to pass over it and engage the interceptor tooth 155.

Coaction of stops with margin counterstop means

As afore-indicated, the toothed wheel 140 is yieldably held in a medial lateral position by spring 153 and the associated mounting, and maintains this position during the passing by of the various stops, which passing causes the wheel to be rotated, see Figure 16. However, when acted upon by one of the margin stops moving in a certain direction, the registry of the stop blades with the wheel teeth 155, 156 prevents rotation of said wheel. Although interception of the stop by tooth 155 tends to turn wheel 140, and this tendency presses tooth 156 upwardly against the trailing stop blade, tending to restore that blade to ineffective position, the stop-detent resists restoring the blade and this resistance, plus the force of the wheel detent 142, 143, holds the wheel 140 nonrotative. Turning of the wheel being thus prevented, said wheel is caused to be carried along bodily with the moving stop, until the wheel engages the appropriate one of two shoulders 159 of a top plate 160 on the housing 42. Said shoulders are shaped to receive the wheel tooth 156 so as to limit this shifting and also to positively prevent rotation of the wheel 140. The limits of wheel shifting, defined by shoulders 159, are determined with the intent of arresting the stops 34^t and 34^r at certain prescribed relative positions, as hereinafter further explained. When the toothed wheel 140 is shifted laterally and engages the corresponding shoulder 159, it is thus locked against turning and arrest of the carriage results, see Figures 14 and 15.

It will now be seen that the margin stop 34^t travelling rightwardly will cause the arrest of the carriage at the selected left margin or line start; likewise, travel of the stop 34^r leftwardly will arrest the carriage at the selected right margin or line end. The tabulator stop 34^t, however, coming into engagement with the counterstop wheel 140, will not cause arrest of the carriage, whether moving in one direction or the other, but will be allowed to pass by in that this stop presents only one set stop blade. During its travel past the wheel 140, the stop 34^t engages the interceptor tooth 155 and causes said wheel to rotate against the action of the detent 142, 143. Wheel 140 continues to turn under influence of the travelling stop until said stop rides clear, at which time the detent cam 142 will have turned to a position wherein its high point is past roller 143 and thus will complete rotation of the wheel, bringing same to rest in a position with the next succeeding interceptor tooth 155 projecting into the stop path. A similar action occurs as the carriage is moved into the range between the

5 margins following margin release beyond either margin. This action, occurring during the leftward, return travel of the left margin stop 34^t, is illustrated in Figure 16. In that the spacing of the blades of this stop is greater than the distance between the right face of tooth 155 and the face 158 of the tooth 156, these stop blades will be out of registry with said teeth and wheel 140 will therefore be permitted to rotate, thus allowing 10 stop 34^t to pass by. Similarly, following release to beyond the right margin, during the rightward return of stop 34^r, said stop will pass by the wheel 140 as the latter is turned. The two blades of this stop, being only one letter space 15 apart, will react with the teeth 155, 156 at that side of the counterstop wheel in the same manner as does the single-blade stop 34^t.

Stop-setting mechanism of modified form

20 The maximum spacing of the two blades constituting either margin stop is that of two letter spaces, for the left margin stop 34^t; in other words, said blades are within the limits of a zone embracing three stop blades. In that the other stops 34^t and 34^r occupy a lesser portion of that zone, it is apparent that any of the various stops 34^t, 34^r, and 34^t may be contained within that three-blade zone. To facilitate the description, the three letter-feed points constituting said zone 30 are indicated in the several front views by A, B, and C, progressing from left to right.

It may be here noted that the two limits of shift of wheel 140, defined by the shoulders 159 are determined with the view to causing arrest of either 35 margin stop within that zone, with each of the stop blades at a certain one of said letter-feed points. That is, in the instance of the left margin stop 34^t, Figure 14, the leftmost blade will be at point A and the other blade will be at point C, and, in the instance of the right margin stop 34^r, Figure 15, the two blades will be arrested at points A and B, respectively. The tabulator stop 34^t, after interception by the tabulating counterstop 103 (see Figure 4 of the first form), will come 40 to rest at the point A. Note that in any of the three instances one of the blades of the arrested stop is at the point A.

The stop-setting mechanism provides three 50 setting members 161, 162, 163, see Figure 12, the upper end of each of which presents a setting finger arranged to engage, respectively, the three stop blades that may be at the points A, B, and C. As shown in Figure 13, the setting member 161 extends only part way down and has a stud 55 164 secured thereto which projects through a slot provided in each of the other setting members 162 and 163. The setting mechanism further includes an actuating member 165 also having a slot through which the stud 164 projects.

60 The members 162, 163, and 165 each has an intermediate lever 166 individually connected to it, the three levers 166 being pivoted intermediate their ends, at 149 on the bracket 148. A key lever, not shown, is provided to actuate each intermediate lever. The arrangement of the train of levers for each member 162, 163, and 165 may be similar to that of the setting mechanism shown in the first form. A spring 167, Figure 12, yieldably holds the setting member 161, and with it 65 the actuating member 165, in the inactive or raised position. A spring, not shown, on each of the levers 166 of setting members 162 and 163, yieldably holds these members in the raised position.

70 It will be now seen that when member 165 is

pulled down by operating its key lever, the stud 164 moves with it and thus pulls the setting member 161 down. The stud 164 moves in the slots in members 162 and 163, and, therefore, these members are not actuated, but are held inactive by their springs. Thus, only the setting member 161 is pulled down and only the blade at the letter-feed point A is set, this single blade becoming a tabulator stop 34^t. It will be further seen that as one of the members 162, 163 is actuated, the stop blade at the corresponding point, either at B or at C, will be set. Actuation of either member 162 or 163, however, operating through stud 164, also pulls down member 161. It follows then that when member 162 is operated, a blade at point B will be set and, simultaneously, a blade will be set at point A; the two blades forming the stop 34^t. It also follows that as member 163 is operated, a blade at point C is set and, simultaneously, a blade is set at point A; the two blades forming the stop 34^t. Prior to each setting operation, of course, the carriage is moved to the letter-feed position at which the particular stop is to be set.

As shown in Figure 13, the tabulator setting mechanism of the modified form may include the preventive device 50—54 by which the setting of a tabulator stop 34^t is prevented unless the stop blade 34, which is aligned with the setting member 161, is a certain number of letter spaces (more than three) away from the nearest set blade. The slot 55 of the feeler 50, in this form, is in vertical alignment with the setting member 161. The feeler 50 is arranged to be swung into the region where the stops are set, by the coaction of the cam slot 53 with the pin 54 on said feeler. In this form, however, the plate 52 having the cam slot, forms part of the actuating member 165, which member is operated only when setting a tabulator stop 34^t. The operation of setting members 162 or 163, which cause the simultaneous actuation of setting member 161, will not operate the preventive device in that member 165 remains inactive during the settings of the margin stop blades.

Line locking

In this modification, the line locking mechanism may be substantially the same as in the first form, the locking lever 86 being arranged for actuation by the shiftable support 141. When the toothed wheel 140 is shifted leftwardly to the position shown in Figure 15, incident to gaging the right margin or line-end limit, the corresponding shifting of support 141 causes lever 86 to lock the typewriter against operation.

Conclusion

It will now be seen that the invention provides a carriage stop mechanism adapted for both margin gaging and tabulating, in which only a single series of identical stop blades are used and in which the blades, when set for any of the several functions, assume corresponding positions on the rack, in alignment with each other lengthwise of the carriage. This desideratum, affording use of a single stop rack of simple, light weight and durable construction, is made possible by the provision of the margin counterstop devices, the sensing means of which, although being acted upon by all the set stops, are coordinated or sensed for carriage-arresting coaction with only certain set stops moving in a certain direction.

The embodiments herein shown present the in-

vention in its entirety, that is, including right and left margin-gaging, tabulating, margin release with automatic restoration, stop-setting, and stop-restoring mechanisms. It is to be understood, however, that certain of the mechanisms may be used in various combinations, omitting others, as may be desired. For example, an embodiment may provide for only margin gaging at the two line-ends, and may exclude the tabulating devices; or it may combine the tabulating mechanism with margin gaging for only the line-start or right margin, etc. Further, while it is desirable to set the stops by a key-controlled mechanism operable from the keyboard of the typewriter, other means of setting the stops may be employed.

Of the two set blades constituting either margin stop, the first blade serves primarily as the margin gage, and the second or companion blade is that which identifies or characterizes the stop, firstly as a margin stop and secondly as either a left- or a right-hand margin-stop. That is, by its presence with the gaging blade, and also by its position-relation thereto, the second stop blade makes of the combined blades a particular margin stop. Although it is preferable, for apparent reasons, to have that second or identifying stop blade on the same rack as the first blade, it is within the scope of the invention to arrange these two differently functioning elements on separate racks or supports, if desired.

Accordingly, the invention may be modified in these and other ways, and may be embodied in various other forms, without departing from its spirit or the scope of the invention as defined in the appended claims.

What is claimed is:

1. In a typewriter having two elements, one a frame and the other a carriage movable on the frame; mechanism providing for selection of carriage locations for effecting certain typewriter functions such as gaging margins, line-end signalling, line locking and tabulating; said mechanism comprising a plurality of members on one of said elements, each adapted for setting to an effective position, to present distinctive groups of set members for individually effecting certain ones of the typewriter functions, the groups being distinguished one from the others by the number of set members in respective groups or by the spacing between the set members of respective groups; and means on the other said element, acting in response to coaction of one member group only, to effect a certain one of the typewriter functions.

2. In a typewriter having two elements, one a frame and the other a carriage movable on the frame; mechanism providing for selection of carriage locations for effecting certain typewriter functions such as gaging margins, line-end signalling, line locking and tabulating; said mechanism comprising a plurality of members on one of said elements, each adapted for setting to an effective position, to present distinctive groups of set members for individually effecting certain ones of the typewriter functions, the groups being distinguished one from the others either by the number of set members in the respective groups or by the spacing between the set members of respective groups; and normally disabled means to effect a certain one of the typewriter functions said means being arranged on the other said element for engagement by the effectively set members and including a device, rendered effective by only one group of the set

members, to condition said means for operation.

3. In a typewriter having two elements, one a frame and the other a carriage movable on the frame; mechanism providing for selection of carriage locations for effecting certain typewriter functions such as determining the line-start, column and line-end positions of typing; said mechanism comprising a series of blades arranged at regular intervals on one of said elements and settable to corresponding effective positions in alignment with each other, the setting of any of said blades in separate groups consisting of pairs of blades of one or another spacing between the blades or consisting of a single blade, affording distinction of the effective set blades according to their intended, respective functions; and normally disabled means arranged on the other of said elements in the path of the effective set blades, to effect a certain one of the typewriter functions incident to carriage travel; said means including a device operable only by one of the groups of set blades, to condition said means for operation.

4. In a typewriter having two elements, one a frame and the other a carriage movable on the frame; mechanism providing for selection of carriage locations for effecting certain typewriter functions such as determining the line-start, and line-end positions of typing; said mechanism comprising a series of blades arranged at regular intervals on one of said elements and settable to corresponding effective positions in alignment with each other, the setting of any of said blades in separate groups consisting of pairs of blades of one or another spacing between the blades, affording distinction of the effective set blades according to their intended, respective functions; and means on the other said element, operable only by one group of two blades having a certain spacing between the blades, to effect a certain one of the typewriter functions incident to carriage movement; said means including a pair of members cooperative with the effective set blades and arranged for movement alternately into and out of the path of the set blades, the members of said pair having a spacing therebetween corresponding substantially to the spacing between the blades of the group by which said means is operable.

5. In a typewriter having two elements, one a frame and the other a carriage movable on the frame; a combined margin-gaging and tabulating mechanism, including a plurality of members on one of said elements, settable to effective positions for cooperation with counterstop means, any single set one of said members being adapted to define a tabulating point and any two set ones of said members set in a certain position-relation being adapted to define a marginal limit; and normally disabled counterstop means on the other said element, arranged in the path of the set members and including a device, operable by the two members set in the certain position-relation, to condition the counterstop means to bar carriage travel only at the marginal limit.

6. In a typewriter having two elements, one a frame and the other a carriage movable on the frame, a margin-gaging mechanism, including a plurality of settable members on one of said elements settable to effective positions for cooperation with counterstop means, two of said members set at a certain position-relation being adapted to define one margin and another two of said members set at a different position-relation being adapted to define the other margin, 75

and normally disabled counterstop means on the other said element, including devices to condition the counterstop means to bar carriage travel in one direction or the other, depending on which two of the set members cooperates with the counterstop means.

7. In a typewriter having two elements, one a frame and the other a carriage movable on the frame; a carriage stop mechanism including a series of blades arranged at regular intervals on one of said elements and settable to corresponding effective positions in alignment with each other, two pairs of said blades set to effective position being adapted to define, respectively, the two marginal limits of a typing line, the blades of each pair having a certain space interval and the two intervals differing; and normally disabled counterstop means arranged on the other said element for cooperation with the set blades including means operative by the blades of one pair to condition the counterstop means to bar carriage travel in one direction and means operative by the blades of the other pair to condition the counterstop means to bar carriage travel in the other direction.

8. In a typewriter having two elements, one a frame and the other a carriage movable on the frame in letter-space increments; a carriage stop mechanism including a series of letter-spaced blades arranged on one of said elements and settable to corresponding effective positions in alignment with each other, two pairs of said blades that are set and have the blades of each pair separated certain numbers of letter spaces, being adapted to define, respectively the two marginal limits of a typing line, the blades of the two pairs having separations of different numbers of letter spaces; and normally disabled counterstop means arranged on the other said element for cooperation with the set blades, including means operative by the blades of one pair to condition the counterstop means to bar carriage travel in one direction and means operative by the blades of the other pair to condition the counterstop means to bar carriage travel in the other direction.

9. In a typewriter having two elements, one a frame and the other a carriage movable on the frame; a combined margin-gaging and tabulating mechanism, including a series of members on one of said elements settable to corresponding effective positions in alignment with each other lengthwise of the carriage for cooperation with counterstop means, two of said members set at a certain space-relation being adapted to define one margin, another two of said members set at a different space-relation being adapted to define the other margin and any single set one of said members being adapted to define a tabulating point; and normally disabled counterstop means on the other said element, including devices, engageable by the set members, to condition the counterstop means to bar carriage travel in one direction or the other depending on which pair of set members cooperates with the counterstop means, said counterstop means also including a normally ineffective tabulator counterstop and manually operable means to render said tabulator counterstop effective.

10. In a typewriter having two elements, one a frame and the other a carriage movable on the frame, and a line-locking device; a margin-gaging mechanism including a series of blades arranged at regular intervals on one of said ele-

ments and settable to corresponding effective positions in alignment with each other lengthwise of the carriage, a pair of said blades set with a certain spacing therebetween being adapted to define a typing line start, a second pair of said blades set to effective position with a different spacing therebetween being adapted to represent a typing line-end; and normally disabled counterstop means on the other said element, including means, operative by the pair of blades set at one spacing for defining the line start, to condition the counterstop means to bar carriage travel in one direction, and normally disabled means to operate said line-locking device, including a device operative by the pair of blades set at the different spacing to represent the line-end, to condition said operating means for operation.

11. In a typewriter having two elements, one a frame and the other a carriage movable on the frame, and a line-end signal device; a margin-gaging mechanism including a series of blades arranged at substantially uniform intervals on one of said elements and settable to corresponding effective positions in alignment with each other lengthwise of the carriage, a pair of said blades set with a certain spacing therebetween being adapted to define a typing line start, a second pair of said blades set to effective position with a different spacing therebetween being adapted to represent a typing line end; normally disabled counterstop means on the other said element, including means, operative by the pair of blades set at one spacing for defining the line start, to condition the counterstop means to bar carriage travel in one direction; and normally disabled means to operate said line-end signal device, including a device, operative by the pair of blades set at the different spacing to represent the line end, to condition the signal device operating means for operation.

12. In a typewriter having a frame and a carriage movable thereon; a combined margin-stopping and tabulating mechanism including a single series of blades on the carriage settable to corresponding effective positions in alignment with each other, a left margin stop being formed of two set blades having a certain spacing apart, a right margin stop being formed of two set blades having a different certain spacing apart and tabulator stops being formed of single set blades; left margin counterstop means and right margin counterstop means on the frame, each including a stopping tooth member and a sensing tooth member and connections between said tooth members to cause them to be moved alternately into and out of the path of the set blades and transversely of said path, the spacing between the two tooth members of each counterstop means being substantially the same as the spacing of the two blades of the corresponding margin stop; means mounting the counterstop means for limited movement bodily with the carriage; and means, effective after limited movement occurs, to lock said tooth members against the transverse movement.

13. In a typewriter having a frame and a carriage movable thereon; a combined margin-stopping and tabulating mechanism including a single series of blades on the carriage settable to corresponding effective positions in alignment with each other, a left margin stop being formed of two set blades having a certain spacing apart, a right margin stop being formed of two set blades having a different certain spacing apart

and the tabulator stops being formed of single set blades; a left margin counterstop and a right margin counterstop on the frame, each presenting a tooth and each arranged for movement of its tooth into and out of the path of the set blades; a control member for each margin counterstop, each presenting a tooth and each arranged for movement of its tooth into and out of the set blade path; connections between each control member and the corresponding counterstop to cause the associated two teeth to move alternately into and out of the set blade path, the spacing between the two teeth of each counterstop and its control member being substantially the same as the spacing of the two set blades forming the corresponding margin stop; means mounting each counterstop and its control member for limited movement bodily with the carriage; and means, effective after the limited movement occurs, to lock the corresponding counterstop against movement from the set blade path.

14. In a typewriter having a frame and a carriage movable thereon; a combined margin-stopping and tabulating mechanism including a single series of blades on the carriage settable to corresponding effective positions in alignment with each other, a left margin stop being formed of two set blades having a certain spacing apart, a right margin stop being formed of two set blades having a different certain spacing apart and the tabulator stops being formed of single set blades; a wheel on the frame having a plurality of identical sets of teeth, each set including one stopping tooth and two sensing tooth members, one for each margin stop, one sensing tooth member having a spacing from the stopping tooth corresponding to the spacing between the blades of one margin stop, the other sensing tooth member having a spacing from the stopping tooth corresponding to the spacing between the blades of the other margin stop; means to yieldably detent said wheel at rotative positions in which one of the stopping teeth projects into the path of the set blades; means mounting said wheel for rotation and for limited movement bodily with the carriage; and means, effective after the limited movement occurs, to lock the wheel against rotation in the direction corresponding to that of the movement of the carriage.

15. In a typewriter having a frame, a motor-impelled, letter-feed controlled carriage and means to release the carriage to motor-impelled travel; a tabulator mechanism including a series of blades on the carriage individually settable from an ineffective position to an effective position to define selective tabulating points; a member on the frame adapted to serve selectively either as a tabulating counterstop to arrest the carriage in cooperation with the set blades or as a restorer to return the set blades to ineffective position, said member being normally disposed out of the path of the set blades; means to positively project said member into said path; and means operable by said carriage-releasing means to yieldingly project said member into said path.

16. In a typewriter carriage stop mechanism having a row of uniformly spaced, settable blades, in which mechanism the blades may be set in various combinations to constitute different groups, the groups differing in the number of blades set or the spacing between the set blades of the group, means to set the blades selectively in any of the various combinations, said means

comprising at least three setting members, means, capable of selective operation in single strokes, to actuate said setting members selectively, and connections between said setting members and said actuating means to operate either a certain one, a certain two or another two of said setting members, according to said selective operation.

17. In a typewriter carriage stop mechanism having a row of uniformly spaced settable blades, in which mechanism the blades may be set in various combinations to constitute different groups, the groups varying in the number of blades set or in the spacing between the blades of the group, means to set the blades selectively in any of the various combinations upon a one-stroke, single key operation, said means comprising at least three setting members, a corresponding number of actuating keys, and connections between said setting members and said keys to operate either a certain one, a certain two or another two of said setting members, depending on which one of said keys is operated.

18. In a typewriter carriage control mechanism providing for selection of carriage locations for effecting certain typewriter functions such as determining the line-start, columnal, and line-end positions of typing, and having a row of settable blades arranged at regular intervals, the blades set to effective position in distinctive groups, one for each typewriter function, defining the desired carriage locations, the groups each consisting of either a single blade or two blades at a certain slight spacing, means to set blades singly and to prevent the setting of a blade as close to an adjacent set blade as the certain slight spacing, said means comprising a manually operable blade setter, a member having a gaging portion extending from the setter in at least one direction along the row of blades to a length exceeding the certain slight spacing, and means operable by said setter for moving the gaging portion of the member into the path of the set blades.

MEIGS W. NEWBERRY.
